(57) CLAIM

The ornamental design for a throwable ball, as shown and described.

DESCRIPTION

FIG. 1 is a front and left perspective view of the throwable ball showing our new design;

FIG. 2 is a left side view thereof, the side opposite being a mirror image; and,

FIG. 3 is a front view thereof; the rear view being the same the same except for the area occupied by the raised lettering showing in broken lines.

The dotted lines are included for the purpose of illustrating portions of the throwable ball that form no part of the claimed design. The appearance within the unshaded end region of FIGS. 1 and 3 likewise forms no part of the claimed design.
